Primary Examiner — Abraham Bahta(74) *Attorney, Agent, or Firm* — Dunlap Bennett & Ludwig, PLLC(57) **CLAIM**

The ornamental design for a travel privacy shell, as shown and described.

DESCRIPTION

FIG. 1 is a front, right, top perspective view of the travel privacy shell, showing our new design;

FIG. 2 is a front, left, top perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines shown in the drawings depict pockets, windows, and mesh material that form no part of the claimed design.
